UNITED STATES PATENT OFFICE.

CORNELIA M. POST, OF PHILADELPHIA, PENNSYLVANIA, ASSIGNOR TO THE PARAFFINE COMPANIES, INC., OF SAN FRANCISCO, CALIFORNIA, A CORPORATION OF NEW JERSEY.

DESIGN FOR LINOLEUM, OILCLOTH, OR FLOOR-COVERING.

59,516.

Specification for Design.

Patented Oct. 25, 1921.

Application filed June 20, 1921. Serial No. 479,122. Term of patent 14 years.

To all whom it may concern:

Be it known that I, CORNELIA M. Post, a citizen of the United States, and a resident of the city and county of Philadelphia, State of Pennsylvania, have invented a new, original and ornamental Design for Linoleum, Oilcloth, or Floor-Covering, of which the following is a specification, reference being had to the accompanying drawing, forming part thereof:

The drawing is a plan view of a piece of linoleum, oilcloth or floor covering illustrating my new design.

I claim:

The ornamental design for linoleum, oilcloth or floor covering, substantially as shown.

CORNELIA M. POST.
